werk, Siemensstadt, near Berlin, Germany

Application October 2, 1937, Serial No. 167,056
In Germany October 3, 1936

22 Claims. (Cl. 179—18)

In remote communication systems, and more particularly in telephone systems, arrangements are already known which render the calling condition at subscribers' lines inoperative as regards its influence on the connecting devices in the exchange if no switching measures for setting up a connection are taken at a calling station within a given time after the call initiating impulse has been transmitted. In one arrangement a special disconnecting relay, which is connected to the subscriber's line on the interruption of the locking circuit by the quick to release cut-off relay, is maintained energized by the calling condition and as a result prevents the calling condition of this line influencing the connecting devices of the exchange.

Arrangements have also been proposed in which while avoiding a special auxiliary relay an existing calling condition is rendered inoperative merely by the cooperation of two relays with which the subscriber's line is already provided for other purposes. Thus, for example, by the interrupting of the locking circuit existing during a call for the slow-to-release cut-off relay and the quick-to-release call relay the first is connected to the subscriber's line and is held energized over this. In another arrangement an auxiliary relay provided for a special purpose (operating a meter) causes the calling condition of the subscriber's line to be rendered inoperative in cooperation with the combined line and cut-off relay in the form of a two-stage relay.

The present invention is based upon the desirability of producing an efficient and simple method of rendering inoperative a calling condition at the subscriber's line in systems in which the subscribers' lines are not provided with any individual call receiving relays. This is achieved in that when a call is set up between the subscriber's line and another line, the cut-off relay associated with the subscriber's line brings a switching means rendering the calling condition of the subscriber's line inoperative under the influence of switching devices arranged in a succeeding portion of the connecting path which characterize the non-performance of switching measures (impulse transmission for setting up a call or the replacement of a receiver for releasing a call) at the calling station. A special switching means or the cut-off relay itself can be used for rendering the calling condition inoperative. In the latter case the cut-off relay is made a two-stage relay which when completely energized prevents the calling condition of the sub-

scriber's line exerting any further influence on the connecting devices of the exchange.

In the case of systems with call finders in which the testing circuit passes over the calling subscriber's line the connection of the switching devices which render the calling condition inoperative to the subscriber's line can take place after the setting of the call finder at the portion of the testing circuit leading to the connecting devices of the exchange, thereby avoiding any special construction of the connecting devices, for example special wipers in the switches or in the case of relay switches special contacts on the switching through relay.

If the calling condition at the subscriber's line is not to be rendered inoperative by the interruption of a locking circuit maintaining the connection because as in the case of subscribers' lines without individual line relays there are not two relays with different release characteristics available considerable difficulties are involved if the position from which the impulse for rendering the calling condition of a line operative proceeds is separated from the line by a number of selecting stages.

In this case also the invention enables the switching means for rendering the calling condition inoperative to be controlled in a particularly simple way in that a metering circuit over which the subscriber's meter is operated is modified so that the switching means of the subscriber's line which result in rendering its calling condition inoperative can be influenced over this circuit.

The drawing indicates one embodiment of the invention to which the latter is not limited.

When the receiver is taken up at the station T_n which has no individual calling relay associated with it in the exchange the start relay A_n common to the subscriber's group energizes in the following circuit: positive, relay A_n , resistance 1, contact 2 T_1 , lead 3, subscriber's station T_n , lead 4, contact 5 T_1 , resistance 6 and negative. At contact 1 T_n the start relay R associated with a free finder link $AS-VW$ is energized over: positive, contacts 7 a_1 and 8 v_1 , relay R and negative. At contact 9 r the circuit for the rotary magnet D_{vw} of the preselector VW of the pre-selector link $AS-VW$ which is set in readiness is closed:—negative, D_{vw} , contact 10 p_1 and 9 r , 50 interrupter 11, and positive.

At contact 12 r the testing circuit is prepared and when a free connecting line which may for example lead to a first group selector is found this circuit is completed over winding II and I 55

of relay P1, contact 72r, wiper 13, contact 14, seizing relay C and positive. Relay P1 energizes and opens contact 10p1 and thereby brings the preselector VW to rest and at contact 15p1 completes the circuit for driving magnet Das of the call finder AS. By short-circuiting its own resistance winding I at contact 26p1 the seized group selector is guarded against seizure by another preselector. At contacts 27p1 and 28p1 testing and locking circuits are closed over the wipers of the call finder.

Before proceeding with the explanation of the switching operations in the preselecting stage it should be mentioned that relay C in the free connecting line which has been found is slow-to-energize and when energized closes inter alia its contact 16c. The vertical magnet H1 of the group selector IGW is, however, prevented from energizing in that the bridge relays A and B in the first group selector are energized over an auxiliary bridge in the preselecting stage completed by the testing relay P1 of the preselector VW in the following path: negative, relay A, contact 17, wiper 68, contacts 18p1, 19v1 and 20r, resistance 21, wiper 22, contact 23, relay B and positive. Relay A opens its contact 24a disposed in series with contact 16c and thereby prevents relay V2 and the vertical magnet H1 from energizing. Contact 25a is closed for purposes which will be explained later.

After relay P1 has energized and has closed contact 15p1 the call finder AS hunts for the calling line because its rotary magnet is energized in the following circuit: negative, rotary magnet 35 Das, contacts 29p2, 15p1 and 9r, interrupter II and positive. When the calling subscriber's line is found the following testing circuit is closed: positive, contact 21p1, winding I of relay P2, contact 11r, wiper 30, contacts 31 and 32t1, lead 40 3, subscriber's station Tn, lead 4, contact 5t1, resistance 6 and negative. In this testing circuit flowing over the subscriber's line relay P2 energizes and brings the call finder to rest by opening contact 29p2, at contact 33p2 switches through 45 the lower switching lead and at contact 34p2 completes the following circuit: positive, contact 28p1, winding II of relay P2, contact 34p2, relay VI, wiper 35, contacts 36 and 37tII, winding I of relay T and negative. In this circuit relays T 50 and VI energize.

Relay VI closes its contact 38v1 and then opens its contact 19v1 thereby opening the auxiliary bridge over contact 20r and resistance 21 and bringing the relays A and B of the first group selector under the influence of the calling subscriber. Through the opening of contact 8v1 relay R is disconnected and through the closing of contact 39v1 the lead from the start contact 1an is switched through to lead 40 leading to the next 55 call finder. Relay R makes a delayed release and switches its contacts 9r, 11r, 72r and 20r back to normal.

At the calling subscriber's line the cut-off relay T which is a two-stage relay is energized 60 in its first stage by the current passing over its winding I and thereupon switches all the contacts indicated by the reference I from the rest position shown into the operated position, consequently contacts 2t1, 5t1 and 32t1 are opened and contact 70 41t1 is closed. Through the opening of contact 32t1 and the closing of contact 41t1 the testing circuit passing over the subscriber's line is switched over. In the portion of the testing circuit leading to the connecting devices of the exchange the switching means which render in-

operative the calling condition at the subscriber's line are connected up. The switching means consist of a winding II enabling the cut-off relay T to be completely energized. Naturally a separate auxiliary relay can be provided for the purpose of rendering the calling condition inoperative. The contacts of relay T bearing the reference II are not influenced when the relay is energized over its winding I but remain in the rest position shown.

When the calling subscriber transmits numerical impulses for setting up the connecting path these are transmitted to the vertical magnet H1 by the closing of contact 24a. The relay V2 disposed in series with the vertical magnet energizes 15 and at contact 42v2 breaks the heating circuit completed at contact 25a over the thermo-relay Th1. The rotary magnet which is not shown is operated in the known way after the termination of the impulse train effecting the vertical 20 setting of the group selector by the release of relay V2 in cooperation with an off-normal contact closed on the first vertical step of the group selector. The group selector now hunts for a free outgoing line in the selected group. On the 25 first rotary step of the switch the rotary off-normal contact 43w is opened so that the thermo-relay Th1 can now no longer be operated.

The case will now be considered in which after the setting of the preselecting devices AS and VW 30 in response to a call initiating impulse the calling subscriber waits too long before operating his dial switch, or the call initiating impulse is falsely produced by a fault in the subscriber's line or at the subscriber's station. After the energizing of 35 relay A in the first group selector of the circuit closes at contact 25a for the thermo-relay Th1 remains operative for a prolonged time; negative, vertical magnet H1, winding I of relay V2, contact 43w, thermo-relay Th1, contacts 42v2 and 25a and 40 positive. In this circuit neither the vertical magnet H1 nor relay V2 (winding I) can energize. The thermo-relay heats up and after the expiry of its heating period closes contact 44th1 thereby preparing for the rendering inoperative of the 45 calling condition at the line which has seized the first group selector.

The subscribers' lines are provided with call meters which are operated by the closing of contact 60, by a meter stepping device Z/S at definite intervals of time after the closing of contact 45zr. Contact 45zr is controlled for example by a relay (not shown) which energizes at the moment when the metering commences. The metering circuit passes as follows: negative, meter Z, contact 46, wiper 47, contact 48ab, wiper 49, contacts 50, 45zr and 60 and positive.

The meter stepping device is also provided with special contacts ab, which are closed at definite intervals of time, and serve to render inoperative 60 the calling condition at subscribers' lines. The contacts ab are operated at different times from contact 60 which serves for influencing the meter. The device can be so arranged that the contacts 60 and the contacts ab are always operated alternately or so that the contacts ab are closed once after contact 60 has been closed a number of times. The switching over of the contacts ab results in switching over the metering circuit. Through the opening of contact 48ab and the 70 closing of contact 51ab, the lead of the metering circuit proceeding from wiper 49 is switched over to wiper 30 of the call finder. At the same time negative potential is connected over contact 52ab. If now at the moment of operation of the 75

contacts 48ab, 51ab and 52ab the thermo relay Th1 has become operative on account of the first impulse train not having been transmitted by the calling subscriber and has closed contact 44th1 the following circuit which operates the cut-off relay T of the subscriber's line in its second switching stage and which passes over the metering circuit and a portion of the testing circuit completed when the call finder was set on the calling line is closed: negative, contacts 52ab, 44th1, and 50, wiper 49, contact 51ab, wiper 30, contacts 31 and 41II, winding II of relay T and positive. All the contacts of relay T indicated by the reference II are now switched over into the operated position, i. e., contact 37tII is opened and contacts 55tII and 56tII are closed. The result of this is that the energizing winding of relay T is connected to the subscriber's line. Relay T remains completely energized in the circuit over the subscriber's line: negative, winding I of relay T, contact 55tII, lead 4, subscriber's station Tn, lead 3, contact 56tII and positive. Relays VI and P2 are deenergized by the opening of contact 37tII and release. Relays A and B at the first group selector release on account of the opening of contact 33p2. The seized switches AS, VW and IGW are thereby released and can be taken into use for other calls.

Instead of bringing about the energization of relay T in the subscriber's line in the second switching stage by the cooperation of the meter stepping device the same operation can be carried out, for example, by disposing an auxiliary relay in series with relay P1, which only responds to strong current. This increase in the current strength can be brought about temporarily by the thermo-relay Th1 in that the contact of the latter short-circuits relay C or a resistance disposed in series with the latter. The auxiliary relay can be connected directly to wiper 30 and can thereby enable the armature of relay T to be fully operated.

The devices, which render the calling condition of a subscriber's line inoperative, if switching operations necessary for the further establishment of the call (for example the impulse transmission) do not become operative within a given time, are also used to release the connecting devices which have been seized by rendering the calling condition at the calling line inoperative if the calling station delays in giving the clearing signal, i. e., does not replace his receiver within a given time after the termination of a call or after the operation of a signal indicating that the call in the desired direction cannot be set up.

The drawing shows the arrangement in which the calling condition at the calling subscriber's line is rendered inoperative if after the operation of the busy signal, which informs the calling station that the connection cannot be established, the clearing signal which, for example, may consist of the interruption of the feeding circuit, is not given within a given time.

65 The calling subscriber causes the first group selector to be raised to that contact level over which calls in the desired traffic direction are set up by dialing an impulse train. If all the outgoing lines are busy the group selector steps 70 around in the known way and closes an overflow contact 61w thereby connecting up the thermo-relay Th2. The thermo-relay heats up and at the same time the calling subscriber receives the busy signal in any desired manner (not indicated).

If now the subscriber does not hang up within the heating period of the thermo-relay Th2 the contact 62th2 is closed thereby preparing for the complete energization of the cut-off relay T over its winding II. This circuit is completed when the meter stepping device ZfS brings about the next influencing of the meter circuit by operating contacts 48ab, 51ab and 52ab.

The effect of the switching over of the metering circuit of the calling line is that the calling condition at the subscriber's line is rendered inoperative as already described and as a result the calling subscriber's station can exert no influence on the connecting devices of the exchange. These are released on account of the release of 15 relays VI, P2, A and B and are made ready to receive other calls.

What is claimed is:

1. In a telephone system, a plurality of lines, switching apparatus having access to said lines, another line, means for seizing said apparatus over said other line to extend a call over an idle one of said plurality of lines, means in said apparatus for determining if an idle one of said plurality of lines is available, means for causing 25 a signal to be reverted over the calling line if all of said plurality of lines are engaged, and means in said apparatus for initiating the release of said apparatus from said line a predetermined interval of time after said signalling 30 if said apparatus is not previously released by the abandonment of said call.

2. In a telephone system, automatic switching apparatus, a subscriber's line having access thereto, a bridge normally across said line, a cut-off 35 relay individual to said line, means for operating said relay to open said bridge when said apparatus is taken into use over said line for the extension of a call, and means for again operating said cut-off relay to thereby initiate the release 40 of said apparatus from said line.

3. In a telephone system, automatic switching apparatus, a subscriber's line having access thereto, a bridge normally across said line, a cut-off relay individual to said line, means for operating said relay to open said bridge when said apparatus is taken into use over said line for the extension of a call, means for controlling said apparatus over said line to extend said call, and means in said apparatus effective if it is not so 50 controlled within a predetermined interval of time for again operating said cut-off relay to thereby initiate the release of said apparatus from said line.

4. In a telephone system, automatic switching apparatus, a subscriber's line having access thereto, a bridge normally across said line, a cut-off relay individual to said line, means for operating said relay to open said bridge when said apparatus is taken into use over said line for 60 the extension of a call, means in said apparatus for causing a signal to be reverted over said subscriber's line, and means effective if said apparatus is not released by the abandonment of said call within a predetermined interval of time 65 thereafter for again operating said cut-off relay to thereby initiate the release of said apparatus from said line.

5. In a telephone system, automatic switching apparatus, a subscriber's line having access thereto, a bridge normally across said line, a cut-off relay individual to said line, means for operating said relay to open said bridge when said apparatus is taken into use over said line for the extension of a call, means for transmitting 75

signals to said apparatus over said line to cause a connection to be extended therefrom, and means in said apparatus for again operating said relay to initiate the release of said apparatus from said line if, after the receipt of said signals, said connection is not so extended.

6. In a telephone system, automatic switching apparatus, a subscriber's line having access thereto, a two-step relay individual to said line, 10 means for automatically taking said apparatus into use over said line responsive to a calling condition thereon, means in said apparatus for thereupon operating said relay a first step and for normally holding said relay so operated while 15 said apparatus is in use, means for operating said relay a second step to thereby cause said apparatus to be released from use, and means for holding said relay as last operated independently of said apparatus so long as the calling condition 20 exists on the line.

7. In a telephone system, automatic switching apparatus, a subscriber's line having access thereto, a two-step relay individual to said line, means for automatically taking said apparatus 25 into use over said line responsive to a calling condition thereon, means in said apparatus for thereupon operating said relay a first step and for normally holding said relay so operated while 30 said apparatus is in use, means for controlling said apparatus over said line to direct the extension of a call thereover, means in said apparatus if it is not so controlled within a predetermined interval of time for operating said relay a second step to thereby cause said apparatus 35 to be released from use, and means for holding said relay as last operated independently of said apparatus so long as the calling condition exists on the line.

8. In a telephone system, automatic switching apparatus, a subscriber's line having access thereto, a two-step relay individual to said line, means for automatically taking said apparatus into use over said line responsive to a calling condition thereon, means in said apparatus for 40 thereupon operating said relay a first step and for normally holding said relay so operated while said apparatus is in use, means in said apparatus for at times causing a signal to be reverted over said subscriber's line, means effective if said apparatus is not released by the removal of said calling condition from said line within a predetermined interval of time thereafter, for operating said relay a second step to thereby cause said apparatus to be released from use, and means for holding said relay as last operated independently 45 of said apparatus so long as the calling condition exists on the line.

9. In a telephone system, subscribers' stations and lines therefor, switching apparatus having access to said lines, means for closing the line loop at any of said stations to initiate a call, 50 means for causing said apparatus to search for the closed line loop of the calling station, a testing circuit completed over the closed line loop at said station to initiate seizure of said line, a relay individual to said line, and means for operating said relay to disconnect said circuit from said line responsive to said seizure.

10. In a telephone system, a subscriber's station and a line therefor, automatic switching apparatus, means responsive to a calling condition 55 upon said line for associating said apparatus with said line, a testing circuit completed over the closed line loop at the subscriber's station responsive to the association of said apparatus with

said line, a cut-off relay, means for seizing said line and for operating said relay responsive to the completion of said circuit, said relay effective to thereupon disconnect said testing circuit from said line, and means in said apparatus for then 60 operating said relay again to thereby initiate the release of said apparatus from said line.

11. In a telephone system, a subscriber's station and a line therefor, automatic switching apparatus, means responsive to a calling condition 10 upon said line for associating said apparatus with said line, a testing circuit completed over the closed line loop at the subscriber's station responsive to the association of said apparatus with said line, a cut-off relay, means for seizing 15 said line and for operating said relay responsive to the completion of said circuit, said relay effective to thereupon disconnect said testing circuit from said line, means for transmitting signals over said line to control said apparatus, and 20 means in said apparatus effective if said signals are not received thereby within a predetermined time after said seizure for operating said relay again to thereby initiate the release of said apparatus from said line.

12. In a telephone system, a subscriber's station and a line therefor, automatic switching apparatus, means responsive to a calling condition upon said line for associating said apparatus with said line, a testing circuit, completed over 30 the closed line loop at the subscriber's station responsive to the association of said apparatus with said line, a cut-off relay, means for seizing said line and for operating said relay responsive to the completion of said circuit, said relay effective to thereupon disconnect said testing circuit from said line, means for transmitting signals over said line to control the extension of 35 a connection therefrom, and means in said apparatus effective if, after said signals are received thereby, said connection is not so extended for operating said relay again to thereby 40 initiate the release of said apparatus from said line.

13. In a telephone system, a subscriber's station and a line therefor, automatic switching apparatus, means responsive to a calling condition upon said line for associating said apparatus with said line, a testing circuit completed over the closed line loop at the subscriber's station responsive to the association of said apparatus with said line, a cut-off relay, means for seizing said line and for operating said relay responsive to the completion of said circuit, said relay effective to thereupon disconnect said testing circuit from said line, means in said apparatus for at 45 times causing a signal to be reverted to the calling subscriber, and means effective if said apparatus is not released by the removal of said calling condition from said line within a predetermined interval of time thereafter for operating 50 said relay again to thereby initiate the release of said apparatus from said line.

14. In a telephone system, a subscriber's station and a line therefor, automatic switching apparatus, means for causing said apparatus to be associated with said line responsive to a calling condition thereon, a testing circuit completed over the closed line loop at the calling station responsive to the association of said apparatus with said line, a two-step relay associated with said line, a circuit for seizing said line and for operating said relay its first step responsive to the completion of said testing circuit to thereby cause said testing circuit to be 65 70 75

- disconnected from said line, another circuit for said relay, means for operating said relay its second step over said other circuit to cause said apparatus to be released from said line.
5. 15. In a telephone system, a subscriber's station and a line therefor, automatic switching apparatus, means responsive to a calling condition upon said line for associating said apparatus with said line, a circuit completed over the closed line loop at the calling station responsive to the association of said apparatus with said line, a two-step relay associated with said line, a circuit for seizing said line and operating said relay its first step responsive to the completion of said first circuit to thereby cause said first circuit to be disconnected from said line and connected to said relay, and means in said apparatus for operating said relay a second step over said first circuit to cause said apparatus to be released from said line.
10. 16. In a telephone system, a subscriber's station and a line therefor, automatic switching apparatus, means responsive to a calling condition upon said line for associating said apparatus with said line, a circuit completed over the closed line loop at the calling station responsive to the association of said apparatus with said line, a two-step relay associated with said line, a circuit for seizing said line and operating said relay its first step responsive to the completion of said first circuit to thereby cause said first circuit to be disconnected from said line and connected to said relay, and means in said apparatus for operating said relay a second step over said first circuit to cause said relay to be disconnected from said second circuit and connected to said line, whereupon said apparatus is released from said line and said relay is maintained as last operated over said line as long as the calling condition exists thereon.
15. 17. In a telephone system, a plurality of subscribers' lines, an automatic switch having access to said lines, a starting circuit for said switch normally connected to all of said lines, a marking circuit for said switch normally connected to one line, said circuits closed responsive to a calling condition on said one line, said switch thereupon effective to seize said line, a single switching device individual to said one line, said device initially operated responsive to said seizure to thereby disconnect said starting circuit and said marking circuit from said line, means effective at times for further operating said device to thereby cause said switch to be released from said line.
20. 18. In a telephone system, subscribers' stations and lines therefor, switching apparatus having access to said lines, a starting circuit connected to all of said lines and completed by a calling condition on any one of said lines to initiate the operation of said apparatus, a testing circuit completed over the closed line loop at the calling station, when said apparatus is associated therewith, a two-step relay associated with said line, means for operating said relay its first step responsive to the completion of said testing circuit to thereby disconnect said starting circuit and said testing circuit from said line, means in said apparatus for operating said relay its second step to cause said apparatus to be released from said line, and means independent of said apparatus for thereafter holding said relay as last operated as long as the calling condition exists on said line.
25. 19. In a telephone system, a subscriber's line, a line relay connected to said line and operated responsive to a calling condition thereupon, a cut-off relay normally disconnected from the line operated thereafter to disconnect said line relay from the line, and means for connecting said cut-off relay to said line to maintain same operated thereover for the duration of said calling condition.
30. 20. In a telephone system, a plurality of subscribers' lines, a line relay connected in common to said lines and operated responsive to a calling condition upon any of said lines, a plurality of cut-off relays each individual to one of the lines, means for operating the cut-off relay associated with the calling line to disconnect said line relay from that line, and means effective at times to connect said cut-off relay to its associated line to maintain said cut-off relay operated thereover for the duration of said calling condition.
35. 21. In a telephone system, a subscriber's line, switching apparatus associated with said line responsive to a calling condition thereupon, a relay individual to said line operated responsive to the association of said apparatus therewith, means effective at times to connect said relay to said line to maintain same operated thereover for the duration of said calling condition thereupon, and means for disassociating said apparatus from said line at said times.
40. 22. In a telephone system, a subscriber's line, switching apparatus associated with said line responsive to a calling condition thereupon, a relay individual to said line operated responsive to the association of said apparatus therewith, means in said apparatus controllable over said line by the subscriber, means effective if the control over said means is not exercised by the subscriber within a certain length of time both to connect said relay to said line to maintain same operated thereover for the duration of the calling condition and to initiate the disassociation of said apparatus from said line.

FRIEDRICH LILL.
